UNITED STATES PATENT OFFICE.

FRANK B. KENNEDY, OF NEW HAVEN, CONNECTICUT, ASSIGNOR TO THE RECORDING
AND COMPUTING MACHINES COMPANY, OF DAYTON, OHIO, A CORPORATION OF OHIO.

COIN AND TICKET SEPARATING MACHIN

1,169,493.

Specification of Letters Patent. Patented Jan. 25, 1916.

Application filed July 5, 1912. Serial No. 707,662.

To all whom it may concern:

Be it known that I, FRANK B. KENNEDY, a citizen of the United States, residing at New Haven, in the county of New Haven and 5 State of Connecticut, have invented new and useful Improvements in Coin and Ticket Separating Machines, of which the following is a specification.

This invention is an improved machine for 10 separating tickets, transfers, passes, or similar objects of light weight from relatively heavy metallic coins or tokens.

The embodiment of this invention which is 15 herein shown is applied to a fare box of the general type employed upon "pay-as-you-enter" cars, in which metallic coins and pasteboard tickets are deposited by the passengers in a common hopper or receiving opening of the fare box, and are then separated 20 for accounting or auditing purposes. In the embodiment herein illustrated, it is assumed that the coins after being separated are registered and delivered to a coin drawer accessible to the conductor for his use in 25 making change, while the tickets after being separated are delivered to a locked box or drawer accessible only to an inspector or other official of the company.

Figure 1 of the drawings is a plan view, 30 Fig. 2 a side elevation and Fig. 3 an end elevation of the exterior of a registering fare box embodying the present invention. Fig. 4 is a side elevation partly in section taken through the longitudinal center of the separator. Fig. 5 is an end view in section taken 35 substantially along the line 5-5 of Fig. 4, chiefly showing the driving connections from the coin registering devices to the revolving separator. Fig. 6 is an end view and Fig. 7 40 a side view of the separator cylinder, removed from the machine. The upper half being shown in section in Fig. 7. Fig. 8 is an end view and Fig. 9 a side view of a modified form and arrangement of the separator. Fig. 10 is an end view showing a 45 modified arrangement for oscillating the ticket cylinder, instead of rotating it.

The fare box 1 of which exterior views are 50 shown in Figs. 1, 2 and 3 is preferably provided with means 2 for attaching it to a rail or other appurtenance of a car. A crank 3 is provided for enabling the conductor or attendant to operate the interior mechanism by turning the crank. A ticket drawer 4 which 55 may be of any desired capacity for receiving

the separated tickets is herein shown to be provided with a lock 5 by means of which the tickets may be made inaccessible to the conductor. A coin drawer 6 for receiving the coins may also be locked if desired. But 60 it is now considered desirable to release the coins for the use of the conductor in making change after they have been registered within the box, in which case the coin drawer is left unlocked and accessible to the conductor. 65 A register 7 which is assumed to be operated by the coins is herein shown as being located in a position to be read through the glazed opening 8. The mechanism of this register and the mechanism by which the coins are 70 registered thereon are not shown herein in detail since they form no part of the invention described and claimed herein.

The inspection chamber 10 through which the coins and tickets are introduced to the 75 machine is or may be of the ordinary construction, having glazed sides through which the coins and tickets deposited by passengers may be examined by the conductor as they slide down the inclined plates 11.

The top of the chamber is provided with 80 slots or perforations of a suitable size for admitting the coins and tickets which the machines are intended to receive. At the bottom of the observation chamber the coins 85 and tickets fall upon a tilting platform (not shown) operated by the external lever 12 by means of which the conductor may discharge its contents at will into the interior mechanism, best shown in side view in Figs. 90 4 to 7 inclusive. When the platform or trap door is thus tilted the coins and tickets fall on an inclined chute 13 which guides them all to the interior of the separator, which

in the present embodiment is illustrated as 95 consisting mainly of a cylindrical drum 14 having its peripheral wall provided with apertures 15 of a size suitable for permitting the exit therethrough of the largest coin which the machine is intended to handle. According to the plan of operation, the tickets employed are made too large to pass through these coin apertures 15 of the separator. The separator is mounted in bearing supports 16 and 17 for rotation upon 100 an axis inclined from the horizontal, so that the tickets and coins tend to gravitate toward the lower discharge end of the separator as the latter is rotated. In order to prevent the coins from sliding too rapidly 110

over their discharge apertures 15, and passing out through the discharge opening 18 at the lower end of the separator, which is intended only for the exit of the tickets, 5 one or more obstructing ribs or dams 20 are provided within the separator. As the lighter tickets accumulate in front of these obstructions, they pile up high enough to pass over the obstruction, whereas the coins 10 being heavier, and being discharged freely through the coin apertures 15 are less liable to pile up, at least sufficiently to pass over the top of the obstruction. For additional safety, however, a plurality of these obstructing ribs or dams are disposed along 15 the length of the separator to take care of coins which in the case of a sudden rapid accession of coins, may be carried over one or more of the obstructing dams 20. The 20 number, height and character of these dams or obstructions should be adapted to the conditions found to exist in any case. In the arrangement illustrated in Figs. 4, 5 and 6 the dams consist of internal annular 25 ribs 20 extending around the inner circumference of the separator, and being appurtenant to the separator, rotate with it. To facilitate carrying the coins and tickets with the rotary movement of the separator, and 30 thus prevent them from remaining too much at the lower portion of the separator, spurs or pins 21 are provided which stir up the tickets and coins and tend to carry them with the rotary movement of the separator 35 until they reach an angle which causes them to fall or slide off. This also facilitates the movement of the tickets over the successive dams 20 toward their discharge opening 18.

The tickets which are discharged through 40 the opening 18 at the end of the separator fall or slide along the passage 22 to the ticket receptacle 4, which may be locked against removal by any except an authorized inspector or collector.

45 The coins which fall through the peripheral coin apertures 15 of the separator are here assumed to fall upon or into the coin plate or hopper 23 of suitable registering mechanism, by means of which they are 50 registered according to their various denominations and the result indicated upon the register 7. It is also here assumed that the separator is driven from a gear 25 of the registering mechanism through a train 55 of gears 26 and 27 meshing with gear teeth 28 upon the periphery of the separator, so that the latter is rotated at a speed suitably related to that of its associated registering mechanism.

60 Figs. 8 and 9 show a modification in which the separator 30 which as in the previous instance is shown to be a perforated cylindrical drum, is mounted for rotation upon an inclined axis, although for convenience of projection is shown in these views in a

horizontal position. The separator is supported at its ends by means of spiders 31 and 32, the former of which is supported for rotation upon and around the fixed central shaft 33, while the hub of the other spider 32 extends through and is journaled in a hub 34 of the delivery chute 35 this being the discharge end of the apparatus. A gear wheel 36 or other suitable driving connection is secured to the hub of the spider 32, by means of which the desired rotary movement is imparted to the separator from the registering or other associated mechanism of the machine. In this modification, the dams 38, forming the obstructions over which the tickets must pass are supported upon the fixed shaft 33 and therefore do not turn with the separator. As shown herein (Fig. 8) the upper edges 39 of these dams are about as high as the axial center of the separator; but these heights may obviously be varied, and the number and the disposal of these dams may be modified to suit the conditions under which the apparatus is to be employed.

Fig. 10 shows a method of oscillating the ticket cylinder instead of rotating it, by means of a crank 42 on the gear 46, connected by the rod 43 to a pin 44 on the cylinder 45.

I claim as my invention:—

1. In an apparatus for separating coins from tickets, a separator provided with discharge apertures of a size to permit the passage of coins but to prevent the passage of tickets, and with another discharge aperture for tickets, said separator having means to retard the passage of the coins toward said ticket discharge aperture without preventing tickets from passing through such aperture.

2. In an apparatus for separating coins from tickets, a separator provided with discharge apertures of a size to permit the passage of coins but to prevent the passage of tickets and with another discharge aperture for tickets located beyond the discharge apertures for the coins, and means arranged between the two kinds of apertures for retarding the movement of the coins toward the ticket discharge aperture without preventing the movement of the tickets toward said ticket discharge aperture.

3. In an apparatus for separating coins from tickets, a separator provided with discharge apertures of a size to permit the passage of coins but to prevent the passage of tickets and with another discharge aperture for tickets located beyond the discharge aperture for the coins, said separator having movement tending to cause both coins and tickets to move toward said ticket discharge aperture, and means arranged between the two kinds of apertures for retarding the movement of coins toward the ticket

discharge aperture and causing the coins to pass through the coin discharge aperture.

4. In coin and ticket separating apparatus, the combination of a rotary separator provided with discharge apertures for the coins, a discharge aperture for tickets, and means for obstructing the movement of the coins away from their discharge apertures toward the ticket discharge apertures.

10 5. In apparatus for separating coins and tickets, the combination of a separator provided with discharge openings for the coins and a larger discharge opening for tickets, means for supporting and rotating the separator on an inclined axis, whereby the direction of gravitation of the coins and tickets is across the coin apertures toward the ticket aperture, and means located between the coin apertures and the ticket aperture for 20 obstructing the flow of coins toward the ticket discharge aperture.

6. In apparatus for separating coins and tickets, a rotary separator having a peripheral surface provided with coin apertures, a ticket aperture, means for obstructing flow of coins and tickets toward the ticket discharge aperture.

7. In an apparatus for separating coins and tickets, the combination with a cylindrical separator to cause the coins and tickets to move lengthwise thereof and provided with coin discharge apertures through its peripheral portion and having a ticket discharge aperture through its end portion, of 35 means for obstructing the flow of coins and tickets along the peripheral portion toward the ticket discharge aperture and for causing the coins to pass through said peripheral apertures.

40 8. In apparatus for separating coins and tickets, the combination of a separator substantially in the form of an open-ended cylinder having one end disposed for receiving the coins and tickets and having its peripheral portion provided with coin discharge openings and its opposite end portion provided with a ticket discharge opening and means to prevent the coins from reaching said ticket discharge opening.

50 9. In apparatus for separating coins and tickets, the combination of a separator in the form of an open-ended cylinder disposed for rotation upon an inclined axis with its upper end located in position for receiving mixed coins and tickets, the peripheral portion of the cylinder being provided with coin discharge openings leading to coin registering mechanism, and the opposite lower open end of the cylinder being connected 60 with a receptacle for receiving the separated tickets through the end of the cylindrical separator.

10. In coin and ticket separating apparatus, the combination, with a rotatable separator arranged to cause the coins and

tickets to move in an axial direction, said separator having a series of discharge openings for the coins and a discharge opening for the tickets arranged beyond the discharge openings for the coins, of means for 70 obstructing the flow of the coins in an axial direction through the separator.

11. In apparatus for separating coins and tickets, the combination of a separator provided with openings through its walls for 75 discharging the coins, means for supporting and rotating the separator on an inclined axis whereby the coins gravitate in an axial direction through the separator, and means for obstructing the gravity flow 80 of the coins in an axial direction.

12. In apparatus for separating coins and tickets, the combination of a separator provided with openings through its walls for discharging the coins, means for supporting 85 and rotating the separator on an inclined axis, whereby the coins gravitate in an axial direction through the separator, and an annular dam for obstructing the flow of the coin axially along the separator.

90 13. The combination, in a fare receiver for coins and tickets, of means for separating the coins or tickets and delivering them to different receptacles, including an open ended cylindrical separator disposed for receiving the mixed coins and tickets in one end and discharging the separated tickets from the other end, the intervening wall of the separator being provided with discharge apertures for the coins and having 95 means to cause the coins to pass through said apertures.

100 14. The combination, in a fare receiver for coins and tickets, of means for separating the coins or tickets and delivering them to different receptacles, of an open ended cylindrical separator disposed for receiving the mixed coins and tickets in one end and discharging the separated tickets to one of said receptacles, the wall of the separator being provided with discharge apertures for the coins, and with barriers for obstructing the flow of coins and tickets longitudinal of the separator.

110 15. In a coin and ticket fare receiver, the combination of an open ended cylindrical separator disposed for receiving the flow of coin and tickets lengthwise through the interior of the separator, discharge openings for the coins located in the peripheral walls of the separator and peripherally disposed dams upon the interior wall of the separator for obstructing the flow of coins and tickets longitudinally through the separator.

120 16. In a coin and ticket fare receiver, the combination of an open ended cylindrical separator disposed for receiving the flow of coins and tickets lengthwise through the interior of the separator, discharge openings for the coins located in the peripheral walls 125 130

of the separator and peripherally disposed dams upon the interior wall of the separator for obstructing the flow of coins and tickets longitudinally through the separator, and a discharge opening for the tickets arranged beyond said dams.

17. In a receiver for cash and ticket fares, the combination of an open-ended separator mounted for rotation upon an inclined axis, means for directing the flow of coins and tickets into the upper open end of the separator, coin discharge apertures in the peripheral wall of the separator, a coin receptacle below the peripheral holes, and a conduit for the tickets leading from the lower open end of the inclined separator.

18. In apparatus for receiving cash and ticket fares, the combination of separate receptacles for the coins and tickets, an open ended cylindrical separator mounted for rotation upon an inclined axis with its lower open end connected with the ticket receptacle, and having peripheral coin apertures leading to the coin receptacle, and means for directing the stream of mixed coins and tickets into the open end of the separator and

means to cause the coins to pass through said peripheral apertures.

19. In apparatus for receiving mixed coin and ticket fares, means for separating the coins and tickets and delivering them to different receptacles, consisting of an open-ended cylindrical separator mounted for rotation upon an inclined axis with its lower open end communicating with the ticket receptacle, coin apertures through the peripheral cylindrical wall of the separator, means for obstructing the flow of the coins and tickets along the separator to cause the coins to pass through said coin apertures, and means for directing the mixed coins and tickets into the upper open end of the separator.

In testimony whereof I have signed my name to this specification in the presence of two subscribing witnesses this 1st day of July, 1912.

FRANK B. KENNEDY.
